UNITED STATES PATENT OFFICE.

EDWARD T. DOWNS, OF CHICAGO, ILLINOIS.

DESIGN FOR A LAMP BOWL.

Application filed July 23, 1924. Serial No. 10,227. Term of patent 3½ years.

To all whom it may concern:

Be it known that I, EDWARD T. DOWNS, a citizen of the United States, residing at Chicago, in the county of Cook and State of Illinois, having invented a new, original, and ornamental Design for Lamp Bowls, of which the following is a specification, reference being had to the accompanying drawing, forming part thereof.

In the drawing, Fig. 1 is a top view of the bowl of my invention; Fig. 2 is a side view; and Fig. 3 is a bottom view.

I claim:

The ornamental design for a lamp bowl, as shown.

EDWARD T. DOWNS.
